UNITED STATES PATENT OFFICE.

EDWARD HILL, OF SALT LAKE CITY, UTAH, ASSIGNOR OF ONE-HALF TO THOMAS A. HILL, OF DENVER, COLORADO.

WINDOW-LOCK.

1,023,647.

Specification of Letters Patent. Patented Apr. 16, 1912.

Application filed April 7, 1911. Serial No. 619,598.

To all whom it may concern:

Be it known that I, EDWARD HILL, a citizen of the United States, residing at Salt Lake City, in the county of Salt Lake and State of Utah, have invented certain new and useful Improvements in Window-Locks; and I do hereby declare the following to be a full, clear, and exact description of the invention, such as will enable others skilled in the art to which it appertains to make and use the same.

This invention relates to improvements in window locks, and particularly to bodily removable locks which may be applied and removed whenever desired.

The object in view is the construction of a locking device formed substantially as a wedge and designed to be placed between the window sash and window frame in such a manner as to lock the sash against any movement which tends to open the same.

A further object of the invention is the arrangement of a wedge lock formed with an elongated body portion having a stiffening member, a pair of points or claw members, and ears which are designed to be used in applying and removing the device, the whole arrangement being such as to present a stiff, strong structure designed to be wedged between a window sash and its retaining frame.

With these and other objects in view the invention comprises certain novel constructions, combinations, and arrangements of parts as will be hereinafter more fully described and claimed.

In the accompanying drawings: Figure 1 is a fragmentary perspective view of a window showing the invention applied thereto. Fig. 2 is a perspective view of an embodiment of the invention. Fig. 3 is a top plan view of the structure shown in Fig. 1. Fig. 4 is an edge view of the structure shown in Fig. 1. Fig. 5 is a section through Fig. 3 on line 5—5. Fig. 6 is a front view of the structure shown in Fig. 2.

Referring to the accompanying drawings by numerals, 1 indicates a window sash and 2 the frame for holding in place the sash. Arranged to be wedged between sash 1 and frame 2 is a substantially wedge shaped locking member 3 which engages the sash and the frame in such a manner as to pre-

vent any substantial upward movement of the sash. The locking member 3 is formed with a body portion 4 having a chamfered or sharpened end 5 which is designed to be forced in on the order of a wedge between the sash 1 and frame 2 when the device is in operation. The body portion 4 is also constructed with a pressed out portion 6 which forms a wedge or bracing member for stiffening the body portion and preventing any bending or mashing of the same.

The front of the body portion 4 is divided and is formed into hook members 7 and 8 having pointed ends 9 and 10 and offset portions 11 and 12. When the device is in operation the pointed ends 9 and 10 are designed to enter frame 2 a sufficient distance for the offset portions 11 and 12 to press against the frame which will prevent any further movement. Arranged to project in an opposite direction to members 7 and 8 are ears 13 and 14 formed with apertures 75 therein, said ears being designed to be engaged by the hand in applying or removing the device. Of course, it will be evident that a cord or some instrument could be caused to remove the ears in applying and 80 removing the device.

The device may be applied to a window sash regardless of the height thereof, that is, whether the same is closed, partially open, or entirely open. If the window is 85 entirely closed the device is grasped by the ears 13 and 14 and the cord connected with sash 1 is temporarily moved slightly away from the window frame and the chamfered portion 5 of body 4 is forced down between 90 the frame 2 and sash 1 until the pointed ends 9 and 10 begin to enter the frame. If any one attempts to raise the window either from the inside or outside when the device is in this position any movement of the window will only act on the device for causing the pointed ends 9 and 10 to enter farther into frame 2, but will not permit a substantial upward movement of the sash. This is also true where the window is partially 95 open, as it is readily evident that the device may be applied to the sash even when the same is partially open so as to prevent any further opening thereof. Of course, the window may be lowered if partially 100 open, but in such an event the device will

remain in engagement with frame 2 and any subsequent opening of the window will be limited by the locking member 3.

What I claim is:

- 5 A window lock comprising a body portion formed substantially flat throughout, and beveled at one end for defining an entering point, and bent down centrally for defining a cord receiving groove and a central longitudinal bracing rib, a pointed end structure extending at an angle to the body portion
- 10

and designed to cause the body portion to be positioned at an angle when in operation, and means extending from the body portion designed to be used when applying and removing the device. 15

In testimony whereof I affix my signature in presence of two witnesses.

EDWARD HILL.
